MUFFLER

Morris Katcher, New York, N. Y.

Application May 11, 1943, Serial No. 486,489

14 Claims. (Cl. 181—69)

This invention relates to mufflers or silencers for use in connection with the elimination of the noise caused by the flow of gases, for example, from the exhaust manifold of internal combustion engines.

It is an object of the invention to produce a muffler having a housing formed of two mating parts which together form the wall of an elongated chamber. Vanes are attached to one part and extend part way across the chamber leaving a space between the end of a vane and the opposite part. Other vanes, alternating with said first vanes, are attached to the other part and extend therefrom part way across the chamber toward the first part leaving a space on the opposite side of the chamber from said first space. The gas is caused to zigzag across the chamber past the vanes on its way through. The construction of the muffler and its method of assembling is made simple by my design. The two mating parts of the housing, each with its vanes previously attached, are crimped together.

Other objects and advantages will become apparent upon further study of the description and drawing, in which:

Fig. 1 is a sectional plan of the rectangular form of my muffler taken along the line 1—1 of Fig. 3.

Fig. 2 is a partial section taken along the line 2—2 of Fig. 1.

Fig. 3 is an end view of the intake end of the muffler.

Fig. 4 is a section taken along the line 4—4 of Fig. 1.

Fig. 5 is a section of an elliptical form of my muffler with the vanes having their free ends substantially parallel to the major axis of the ellipse, a part of the upper vane being broken away to show the one beneath.

Fig. 6 is a section of an elliptical form of my muffler with the vanes having their free ends substantially parallel to the minor axis of the ellipse, a part of the upper vane being broken away to show the one beneath.

Fig. 7 is an elevation of one of the vanes shown by itself, which vane is used in the muffler of Fig. 6.

Fig. 8 is a section through a vane such as the one shown in Fig. 7, except that it has a corrugated surface, and

Fig. 9 is a section of a cylindrical form of my muffler a part of the upper vane being broken away to show the one beneath.

The muffler of Figs. 1—4 has a housing of two elongated parts, each part being in the form of an angle with flanges extending therefrom. Part 10

is provided with a flange 11 and a flange 12, while part 13 is provided with a flange 14 nesting in flange 12, the latter being crimped about it. Flange 15 of part 13 is crimped about flange 11. Parts 10 and 13 when fastened together form the side wall of an elongated chamber 20.

Vanес 16 are attached to part 10 by means of their flanges 18. In a like manner vanes 17 are fastened to part 13 by means of their flanges 19. The fastening of the flanges to the parts of the housing is preferably by spot welding. Vanes 16 extend part way across chamber 20, a space being left between the end of a vane and part 13. Vanes 17, which alternate along the length of chamber 20 with vanes 16, extend part way across said chamber from part 13, a space being left between the end of each vane 17 and part 10.

End piece 21 serves as the end wall of the chamber at its inlet end, sleeve connection 22 being mounted on it for attachment to say the exhaust of an internal combustion engine. In a similar manner, end piece 23 serves as the end wall of the chamber at its discharge end, the slowed down gas leaving the chamber through sleeve 24.

It is to be noticed that the spacing of vanes 16 and 17 increases as the discharge end 23 of the chamber is approached.

In operation, the exhaust gas as violently discharged from the engine is received in inlet sleeve 22. In entering the chamber 20 it strikes against the first vane 16, is deflected sideways, strikes housing part 13 from whence it passes through the space between the end of vane 16 and housing part 13. It then passes over vane 17 and through the space between the latter and housing part 10, continuing to zigzag across the successive vanes and through the spaces between the end of the vanes until it is discharged through sleeve 24. The turbulence given the gas stream because of its tortuous path and the increased spacing of the vanes toward the discharge end of the muffler slow down the velocity of the gas to such an extent that but little sound is produced when the gas is discharged into the air.

Except for the spacing of and location of vanes 16 and 17 parts 10 and 13 are substantially alike which is advantageous to their quantity production. The method used in assembling the muffler, is to fabricate parts 10 and 13 and attach their respective vanes. With the two halves of the muffler thus prepared, they are brought together, the vanes of one coming in between the vanes of the other, said halves then being fastened to each other along their longitudinal edges by crimping flange 12 over flange 14 and flange 15

over flange 11. End pieces 21 and 23 are then inserted at the ends of the halves and spot welded to them.

In the modified form of muffler shown in Fig. 5, the casing or housing is of substantially elliptical form. The two halves or parts 25 and 26 of the ellipse are substantially identical. The edge of each half occurs at the major axis of the ellipse. Half 25 has an outstanding flange 27 over which is crimped flange 30 of half 26. In a similar manner, half 26 has an outstanding flange 28 over which is crimped flange 29 of half 25. Vanes 31 are spot welded at their flange 33 to half 25, while vanes 32 are spot welded at their flange 34 to half 26 said vanes alternating along their halves of the housing or casing as vanes 16 and 17 of Fig. 1 alternate along their parts 10 and 13. Vanes 31 and 32 extend laterally in a direction parallel to the minor axis of the ellipse across the chamber formed by said halves 25 and 26. Said vanes extend well over half way across the chamber, a space being left between the end of each vane and its opposite half of the housing.

Fig. 6 also shows a muffler with a substantially elliptical casing, the part 35 thereof being crimped to part 36 as in the case of the muffler of Fig. 5. Vanes 37 are attached to part 35 while vanes 38 are attached to part 36. The vanes extend in opposite directions from their parts, extending in a direction parallel to the major axis of the ellipse. They extend a substantial distance across the chamber, a space being left between their ends and the housing on opposite sides of the housing.

Fig. 9 shows a muffler with a substantially cylindrical casing, the parts 39 and 40 being substantially semicylinders which are crimped together at their longitudinal edges. Vanes 41 are attached to part 39, while vanes 42 are attached to part 40. The vanes extend across the chamber well beyond the longitudinal edges of their parts, a space being left between the end of each vane and the opposite part of the housing.

The mufflers of Figs. 5, 6 and 9 are assembled in a similar manner to the muffler of Figs. 1 to 4. Each part has its vanes attached to it before assembly. The parts are then crimped together, the vanes of one part alternating with the vanes of its mate.

Instead of having the vanes formed with plane surfaces, they may be corrugated as shown in Fig. 8. The corrugations 43 extend at right angles to the path of the gas on its way over the vane, increasing the turbulence of the gas thereby.

I claim:

1. A muffler including a housing formed of two elongated oppositely disposed concave parts fastened together to form the wall of an elongated chamber, vanes fixedly attached to one part and unattached to the other extending therefrom across the chamber, a space being left between an end of the vanes and the housing, other vanes fixedly attached to the other part of the housing, extending therefrom in the opposite direction from said former vanes, said latter vanes being unattached to the first part a space being left between an end of the latter vanes and the opposite side of the housing from said first space, the vanes attached to one part alternating with the vanes attached to the other part, whereby gas entering one end of the chamber is caused to have a tortuous path from one side of the housing to the other at the vanes on its way through said spaces.

2. A muffler including a housing formed of two oppositely disposed parts fastened together to form the wall of an elongated chamber, vanes having a flange extending part way around their edge, each vane being unattached to one part and having its flange fixedly attached to the other part, the vanes being fastened alternately, one to one part and one to the other part, each vane contacting the inside of the housing along its periphery except for a portion substantially less than half the length of said periphery, the vane at said portion being spaced from the housing, succeeding vanes being spaced from opposite sides of the housing, whereby gas entering one end of the chamber is caused to have a tortuous path from one side of the housing to the other at each vane on its way through.

3. A muffler including a housing formed of two parts fastened together in oppositely disposed positions to form the wall of an elongated chamber, vanes fixedly attached to one part and unattached to the other extending therefrom across the chamber, a space being left between an end of the vanes and the housing, other vanes fixedly attached to the other part of the housing, extending therefrom in the opposite direction from said former vanes, said latter vanes being unattached to the first part, a space being left between an end of the latter vanes and the opposite side of the housing from said first space, the vanes attached to one part alternating along the length of the chamber with the vanes attached to the other part, except for the spacing of the vanes, one part being substantially the duplicate of the other, gas entering one end of the chamber is forced through it in a tortuous path from one side of the housing to the other at the vanes on its way through said spaces.

4. A muffler including a housing formed of two parts fastened together in oppositely disposed positions to form the side wall of an elongated chamber, pieces extending laterally between the ends of said parts and fastened thereto, said pieces forming the end walls of the chamber, vanes fixedly attached to one part and unattached to the other extending laterally therefrom across the chamber, a space being left between an end of the vanes and the housing, other vanes fixedly attached to the other part of the housing, extending laterally therefrom in the opposite direction from said former vanes, said latter vanes being unattached to the first part, a space being left between an end of the latter vanes and the opposite side of the housing from said first space, the vanes attached to one part alternating along the length of the chamber with the vanes attached to the other part, whereby gas entering one end of the chamber is caused to have a tortuous path from one side of the housing to the other at the vanes on its way through said spaces.

5. A muffler for use in an internal combustion engine, said muffler including a housing formed of two parts fastened together to form the side wall of an elongated chamber, pieces extending laterally between the ends of said parts and fastened thereto forming the end walls of the chamber, means on one end wall for connecting the chamber with the exhaust of the engine, the other end wall having an opening therein for the discharge of the gas from the chamber, vanes fixedly attached to one part and unattached to the other extending laterally well across the chamber, a space being left, however, between an

end of the vanes and the second part of the housing, other vanes fixedly attached to the second part of the housing and unattached to the first part, said latter vanes also extending laterally well across the chamber, a space also being left between the end of the latter vanes and the first part of the housing, the vanes attached to the first part alternating along the length of the chamber, whereby gas entering one end of the chamber is caused to have a tortuous path from one side of the housing to the other at the vanes on its way through said spaces.

6. A muffler including a housing enclosing an elongated chamber, vanes extending well across the chamber from one side of the housing but leaving a space between an end of the vanes and the opposite side of the housing, other vanes alternating along the length of the chamber with the first vanes extending well across the chamber from said opposite side of the housing but leaving a space between the end of the latter vanes and the first side of the housing, the longitudinal spacing between successive vanes increasing from one end of the chamber to the other, said housing having an opening for receiving gas under pressure at the end of the chamber where the vanes are closer together, and another opening at the other end of the chamber for the discharge of the gas, gas entering the chamber at the receiving end is forced through it in a tortuous path from one side of the housing to the other at each vane on its way through said spaces.

7. A muffler including a housing formed of two parts fastened together in oppositely disposed positions to form the wall of an elongated chamber, vanes fixedly attached to one part and unattached to the others extending laterally therefrom across the chamber, a space being left between an end of the vanes and the other part of the housing, other vanes fixedly attached to said other part of the housing extending in the opposite direction from said former vanes across the chamber, said latter vanes being unattached to the first part, a space being left between the end of said other vanes and the first part of the housing, the vanes attached to one part alternating along the length of the chamber with the vanes attached to the other part, the spacing between successive vanes increasing from one end of the housing to the other, except for the spacing of the vanes, one part being substantially the duplicate of the other, one part having a fold over the other at their edges for holding them together, said housing receiving gas under pressure at the end of the chamber where the vanes are closer together, gas entering the chamber at said latter end is forced through the chamber in a tortuous path from one side of the housing to the other at the vanes on its way through said spaces.

8. A muffler including a housing formed of two elongated parts each in the form of an angle, said parts being fastened together substantially at their longitudinal edges in oppositely disposed positions to form the wall of a chamber quadrilateral in cross section, vanes fixedly attached to one angle and unattached to the other extending therefrom well across the chamber toward the second angle, a space being left between the end of the vanes and the second angle, other vanes fixedly attached to said second angle extending therefrom well across the chamber toward the first angle, said latter vanes being unattached to the first part, a space being left between the end of the second vanes and the first angle, the vanes

attached to one angle alternating along the length of the chamber with the vanes attached to the other angle, gas entering one end of the chamber is caused to have a tortuous path from one side of the housing to the other at the vanes on its way through said spaces.

9. A muffler including a housing formed of two concave elongated parts curvilinear in cross section, said parts being fastened together at their longitudinal edges in oppositely disposed positions to form the wall of a chamber, vanes fixedly attached to one part and unattached to the other extending laterally therefrom well across the chamber but stopping short of the other part leaving a space thereby between its edge and said other part, other vanes fixedly attached to said other part extending therefrom in the opposite direction from said first vanes leaving a space between the first part of the housing and the edge of said other vanes, said latter vanes being unattached to the first part, the vanes attached to one part alternating along the length of the chamber with the vanes attached to the other part, whereby gas entering one end of the chamber is caused to have a tortuous path from one side of the housing to the other at the vanes on its way through said spaces.

10. A muffler including a housing formed of two elongated parts substantially semi-elliptical in cross section, the longitudinal edges of said parts being substantially at the major axis of the ellipse, said parts being fastened together substantially at their longitudinal edges in oppositely disposed positions to form an elongated substantially elliptical chamber, vanes fixedly attached to one part and unattached to the other extending well across the chamber in a direction parallel to the minor axis of the ellipse, a space being left between the end of the vanes and the other part of the housing, other vanes fixedly attached to the other part of the housing extending well across the chamber in an opposite direction from the first vanes but also parallel to the minor axis of the ellipse, said latter vanes being unattached to the first part, the vanes attached to one part alternating along the length of the chamber with the vanes attached to the other part, whereby gas entering one end of the chamber is caused to have a tortuous path from one side of the housing to the other at the vanes on its way through said spaces.

11. A muffler including a housing formed of two elongated parts fastened together substantially at their longitudinal edges in oppositely disposed positions to form an elongated substantially elliptical chamber, vanes fixedly attached to one of said parts and unattached to the other, extending laterally therefrom part way across the chamber in a direction parallel to the major axis of the ellipse leaving a space thereby between the end of the vanes and the other part of the housing, other vanes fixedly attached to the other part of the housing extending laterally therefrom part way across the chamber in an opposite direction from the first vanes but also parallel to the major axis of the ellipse, said other vanes leaving a space between their ends and the first part of the housing, said latter vanes being unattached to the first part, the vanes attached to one part alternating along the length of the chamber with the vanes attached to the other part, whereby gas entering one end of the chamber is caused to have a tortuous path from one side of the housing to the other at the vanes on its way through said spaces.

12. A muffler including a housing formed of two

elongated parts, substantially semi-circular in cross section, said parts being fastened together substantially at their longitudinal edges in oppositely disposed positions to form an elongated cylindrical chamber, vanes fixedly attached to one part and unattached to the other extending part way across the chamber but beyond the junction of said parts, a space being left between the end of the vanes and the other part, other vanes fixedly attached to the other part of the housing extending part way across the chamber in the opposite direction from the first vanes, said other vanes extending beyond the junction of the parts on the other side thereof from said first vanes, a space being left between the ends of said other vanes and the first part of the housing, said latter vanes being unattached to the first part, the vanes attached to one part alternating along the length of the chamber with the vanes attached to the other part, whereby gas entering one end of the chamber is caused to have a tortuous path from one side of the housing to the other at the vanes on its way through said spaces.

13. A muffler including a housing enclosing an elongated chamber, vanes extending laterally well across the chamber from one side of the housing but leaving a space between an end of the vanes and the opposite side of the housing, other vanes alternating along the length of the chamber with the first vanes extending laterally well across the chamber from said opposite side of the housing but leaving a space between the end of the latter

5 vanes and the first side of the housing, said vanes being formed with corrugations extending substantially at right angles to said lateral direction, gas entering the chamber at one end being caused to have a tortuous path from one side of the housing to the other at the vanes on its way through said spaces.

10 14. A muffler including a housing enclosing an elongated chamber, vanes extending across the chamber from one side of the housing but leaving a space between an end of the vanes and the opposite side of the housing, other vanes, alternating along the length of the chamber with the first vanes, extending across the chamber from said opposite side of the housing but leaving a space between the end of the latter vanes and the first side of the housing, the longitudinal spacing between successive vanes at one part along the length of the chamber being greater than said latter spacing at another part of the chamber, and the space between the end of the vanes and the housing being greater where the vanes are farther apart than where they are closer together, said housing having an opening for receiving gas under pressure at one end of the chamber, and another opening at the other end of the chamber for the discharge of the gas, gas entering the chamber at the receiving end being forced through it in a tortuous path from one side of the housing to the other at the vanes on its way through said spaces.

25 30 MORRIS KATCHER.
